UNITED STATES PATENT OFFICE

2,116,349

HAIR WAVING DEVICE

Clara F. Harris and Willard A. Tripp, Kansas
City, Mo.

Application March 15, 1937, Serial No. 130,974

9 Claims. (Cl. 132—36)

This invention relates to hair waving devices and particularly to the type wherein the hair is waved when in substantially the same position it is to maintain on the scalp, and also contemplates the use of the well known exothermic material containing pad such as disclosed in United States Letters Patent No. 1,875,228, issued August 30, 1932.

The principal object of this invention is the provision of a hair waving device having a series of interconnected curling sections, each adapted to receive and clamp a tress of hair adjacent the base thereof, and having common means for producing similar waves in the several tresses.

15 A further object of the invention is to produce an apparatus for the waving of hair which will be relatively simple in its construction and application, and which will insure uniformly good results in successive waving operations.

20 Further objects of the invention will appear from the following description, in which preferred embodiments of the invention have been set forth in detail in conjunction with the drawing.

Referring to the drawing:

25 Figure 1 is a plan view of a hair waving device, with certain parts removed for clearness, embodying this invention.

Fig. 2 is a cross sectional view taken on line II—II of Fig. 1, with all the parts in position to 30 wave the hair.

35 Fig. 3 is a fragmentary side elevation of the device.

Fig. 4 is a fragmentary view of the device, showing the reverse side to that shown in Fig. 3.

35 Fig. 5 is a sectional view, taken on line V—V of Fig. 1, and,

Fig. 6 is a reduced plan view of the hair spacing pad.

Throughout the several views like reference 40 characters refer to similar parts, and the numeral 10 designates a base plate, arcuate in one direction, to substantially conform to the curvature of the head and having a series of substantially parallel, elongated slots 12 and upstanding walls 45 14 at similar sides respectively of said slots. A resilient pad 16, made of a suitable material such as rubber, is shaped to conform to the general contour of the base plate, with tongues 18 formed therefrom to rest against the inner surface of walls 14 to produce a resilient clamping jaw. This pad 16 is cemented or otherwise secured in position as shown in Fig. 2.

Slidably mounted on the upper side of base 10 is a clamping jaw 20, with its clamping edge 22 in alignment and associated with the adjacent slot

12. A resilient pad 24 is provided on the edge 22 to co-operate with tongue 18 to clamp the tress of hair 26 adjacent its base. This clamping jaw 20 rests at its one end against the guide flange 28 formed upwardly from base plate 10, and is provided with spaced-apart, upwardly extending lugs 30. A slide bar 32, having a flanged edge 34 positioned in groove 36 formed on the rear side of wall 14 to prevent transverse movement thereof, is provided with diagonally disposed slots 38 through which the lugs 30 extend. The outer end of slide bar 32 is provided with an upturned ledge 40, by means of which it may be moved longitudinally to cause clamping jaw 20 to move transversely across slot 12 and cause a pinching of the 15 tress of hair between the members 18 and 24. When slide bar 32 has been moved to the end of its travel, the lugs 30 will rest in respective recesses 42 formed at the outer end of slots 38 to prevent accidental movement of slide bar 32.

20 The conventional hair clamping spool 44 which jaw 46 is rotatably mounted in bearing members 47 at one end of base 10 in parallel relation with slots 12. The spool 44 is provided with a handle 48, by means of which it may be operated to wind and tension the tresses of hair. To prevent accidental unwinding of the tresses during the waving and curling operation, a ratchet 50 is formed on spool 44 and a resilient pawl 52 co-operates 25 with the teeth thereof to preclude reverse movement of the spool. Bail 45, pivoted at its opposite end 49 to bearing members 47, secures the spool in position and also serves to position the outer pad as hereinafter set forth.

30 For producing the proper curvature of the hair, 35 segmental cylindrical, perforated, members 54, hinged at their one end as at 56 to base 10, are adapted to be moved between adjacent walls 14. A hinged latch 58, provided with notch 60, is adapted to receive the free end of 54 to hold it in 40 the operative position.

An exothermic material containing pad 62 is now placed over the device and secured in position by hinged bars 64, which are secured in the operative position by means of yoke 66 carried by 45 latch 58. For convenience of operation, bar 64 is provided with an operating knob 68.

The outer wall 14 farthest removed from spool 44 is curved inwardly at 70 to receive the end portion of pad 62 to hold it in position. The end portion 50 of pad 62 adjacent the spool passes beneath bail 45 and is turned downwardly to partially surround spool 44.

To facilitate proper division, shaping and spacing of the tresses of hair, the base pad 12 is pro- 55

vided. This pad 62 consists of a flexible, soft material such as felt or the like, and is provided with slits 74 which are respectively positioned in register with slots 12.

5 In the operation of the device a tress of hair 26 is drawn through each of the slits 74, then through corresponding slots 12 in base 10. The slide bars 32 are now moved inwardly until the separate tresses are securely clamped between their respective jaws. The free ends of the tresses are then positioned in the direction of the spool 44 and with the tresses laying one on top of the other and above walls 14, the members 54 are then placed in the operative position above the tresses 15 to press them downwardly between the walls 14 so that they will take on a waved shape in the general position they will assume on the scalp after being curled. The tresses farthest from the spool 44 may be too short to reach the spool, however, this will not be objectionable since a sufficient amount of hair will be engaged by the spool to permit the desired amount of tightening of the tresses. In certain instances where the hair is sufficiently long, the ends of all the tresses will 25 be wound on the spool. While it is possible to lay one tress of hair on the preceding tress to prevent entanglement of the strands, yet it is common practice for the operator to use a comb to maintain the hair of the various tresses in proper relation. It is apparent that certain of the waves 30 produced will consist of hair from several of the tresses, and that each tress does not produce a separate and distinct wave.

The ends of those tresses that are long enough 35 are now inserted beneath the jaw 46 of spool 44, and the end portions of the tresses are wound about the spool 44 until a proper tension is exerted on the hair to facilitate the best waving of the hair. Pad 62 is now positioned as shown in Fig. 40 2, with the swinging bars 64 in the operative position to secure the pad in position. The pad 62 being moistened, produces sufficient heat to cause a permanent waving of the tresses, and when removed from the waving device, will require very 45 little arranging on the scalp, due to the fact that they will maintain substantially the same position relative to the scalp as they had during the waving operation.

It is suggested that more spools might be added 50 to form more end curls in certain cases, however, this would only require duplicating the spool structure as shown.

The similarity of the waves in the various tresses will naturally be very much alike, since 55 they are made by the same means as corresponding sections of the tresses.

It is apparent that the present invention will produce a new and novel effect in the permanent waving of the hair.

60 What we claim is:

1. In a hair waving device, a plurality of spaced-apart clamping means, each adapted to grip a separate tress of hair adjacent the base thereof; waving means associated with each of 65 said clamping means whereby said tresses are secured in substantially a common undulated path from their respective clamping means; and means for heating said tresses of hair while in the waved position.

70 2. In a hair waving device, a plurality of spaced-apart, elongated clamping means, each adapted to grip a tress of hair adjacent the base thereof; a spool adapted to receive the end portions of each of said tresses; means between adjacent clamping means to wave said tresses of 75

hair; and means for heating said tresses of hair while in the waved position.

3. In a hair waving device, a series of spaced-apart, substantially parallel clamping means, each adapted to grip a tress of hair adjacent the 5 base thereof; a rotatable spool at one end of the series of clamping means adapted to receive the end portions of certain of said tresses; means intermediate adjacent clamping means whereby said tresses are held in an undulated form; and means for heating said hair tresses.

4. In a hair waving device, a series of spaced-apart, substantially parallel clamping means arranged in arcuate relation, each clamping means adapted to grip a tress of hair adjacent the 15 base thereof; a rotatable spool, positioned at one end of said series of clamping means, adapted to receive the end portions of some of said tresses; means intermediate adjacent clamping means whereby the tresses of hair are secured in an undulated path from their respective clamping means toward said spool; and means for heating said tresses.

5. In a hair waving device, a series of spaced-apart, clamping means, each adapted to grip a 25 tress of hair adjacent the base thereof; a rotatable spool adapted to receive the end portions of some of said tresses and tension said tresses between said spool and said clamping means; means intermediate adjacent clamping means whereby 30 said tresses are secured in an undulated path from their respective clamping means toward said spool; and means for heating said tresses of hair.

6. In a hair waving device, an arcuate base 35 plate having a series of axially disposed slots formed therethrough, and an upturned wall adjacent each slot; a clamping means associated with each slot to clamp a tress of hair adjacent the base thereof; a rotatably mounted spool carried by said base at one end of said series of slots to receive the end portions of certain of said tresses, and to tension the tresses over said walls; a transversely arcuate member adjustable to be positioned between adjacent walls to cause said 45 tresses to assume an undulated form; and means for heating said tresses.

7. In a hair waving device, an arcuate base plate having a series of axially disposed slots formed therethrough and an upturned wall adjacent each slot; a clamping means associated with each slot to clamp a tress of hair adjacent the base thereof; a flexible pad at the under side of said base plate having slits formed therein to register with said slots, and adapted to receive 50 said hair tresses below said base plate; a rotatably mounted spool carried by said base at one end of said series of slots to receive the end portions of some of said tresses, and to tension the tresses over said walls; a transversely arcuate member adjustable to be positioned between adjacent walls to cause said tresses to assume an 55 undulated form; and means for heating said tresses.

8. In a hair waving device, an arcuate base 60 plate having a series of axially disposed slots formed therethrough, and an upturned wall adjacent each slot; a clamping means associated with each slot to clamp a tress of hair adjacent the base thereof; a rotatably mounted spool carried by said base at one end of said series of slots to receive the end portions of some of said tresses, and to tension the tresses over said walls; a hinged member adapted to be positioned to offset 65 said tresses between adjacent walls; a heating 70

pad adapted to be positioned on top of said hinged member; and adjustable bars to secure said heating pad in the operative position.

9. In a hair waving device, a series of spaced-apart, substantially parallel clamping means each adapted to grip a tress of hair adjacent the base thereof, said clamping means having means for securing it in the operative position; a ro-

tatable spool at one end of the series of clamping means adapted to receive the end portions of a plurality of said tresses; means intermediate adjacent clamping means whereby said tresses are held in an undulated form; and means for heating said hair tresses. 5
